YARN WINDING MACHINE

Ernst Schweizer, Zurich, Switzerland

Application January 20, 1931, Serial No. 510,022
In Switzerland December 10, 1929

1 Claim. (Cl. 242—18)

The subject of this invention is a machine for the parallel winding of yarns on to bobbins, which also enables different lengths of stroke or winding to be arranged for, the stroke of the thread 5 guide remaining invariable during the winding operation when once set for the desired amplitude.

To enable the speed at which the yarn runs on to the bobbins to be maintained at a constant 10 value as the diameter of the bobbins increases in such machines, an automatic reduction of the rotational speed of the bobbins is combined with the winding apparatus in the new machine.

In certain known winding machines of this 15 type, although they can be adjusted for different lengths of winding, that length diminishes during the winding operation. These machines furnish bobbins with tapering ends, or, in order to obtain various lengths of winding with the 20 same machine, the stroke eccentrics are interchangeable.

In the new machine on the contrary, the greatest 25 variety of lengths of winding can be obtained by means of a simple device and in a rapid, accurate and reliable manner, in that the thread guide is correspondingly displaced on an obliquely disposed cam, whereby the desired adjustment of length is obtained.

Uniform yarn winding speeds with increasing 30 diameter of the bobbin are known. They are obtained either by roller drive on the bobbin itself, or else by mounting on the bobbin a contact roller which, as the bobbin diameter increases, receives a movement which is transmitted through 35 a device to a friction-wheel mechanism for retarding the spindle speed. In both these cases, the bobbin material suffers considerably, and is abraded and damaged by the rollers.

Ratchet mechanism for producing uniform yarn 40 winding speed as the bobbin diameter increases, is also known in order to produce a variation of drive on the friction-wheel mechanism. In such cases, however, the requisite ratchet motion is again derived from the rotation of the bobbins 45 through a roller which also damages the material on the bobbin. Such ratchet mechanism, moreover, has to be adjusted by hand.

The combination of ratchet mechanism with 50 depressible thread guides is also known, in which the descent sets up a movement which is utilized for varying the drive so as to feed the yarn on to the bobbins at uniform speed.

The attainment of such uniform speed with increasing bobbin diameter is effected, in accordance 55 with the present invention, by means of a

ratchet mechanism which receives its automatic ratchet movement through the dependency of the shaft carrying the cams and is combined with the friction-wheel mechanism through a direct rod connection for effecting the reduction. 60

A typical embodiment of the invention is illustrated in the accompanying drawings.

Fig. 1 is a plan,

Fig. 2 a side elevation,

Fig. 3 a cross section along I—I of Fig. 1, 65

Fig. 4 a cross section along II—II of Fig. 1,

Fig. 5 a detail of the ratchet mechanism, and

Fig. 6 an elevation of the adjusting device.

The coacting main parts of the machine are: the drive for the machine and the bobbins, the 70 main shaft of the machine, the thread guide and adjusting device, the ratchet mechanism, and the stop motion.

The construction of these parts will first be explained, followed by the manner in which the 75 machine functions.

As shown in Figs. 1 and 2, the drive for the machine and the bobbins consists of a motor-driven shaft 1 carrying a friction wheel 2, which is longitudinally displaceable (for example on a feather) and actuates a friction wheel 3. The wheel 2 is provided with a groove 47, which is engaged by a roller 46 carried by an arm 45 fixed on a rockable shaft 44, mounted in opposite side walls of the casing 23. The friction wheel 3 is seated on the bobbin drive shaft 4 having the pinion 5 from which the drive is transmitted, through countershaft gears 6, 8 on the pin 7 pinion 9 on the main shaft 10, to the small pinion 11 on the other bobbin drive shaft 12. One of 90 the bobbins S is shown in position between the end of the shaft 12 and the back support 48 which is adjustably mounted on the arm 49 extending from a wall of the casing 23.

The main shaft 10 is driven through the same 95 countershaft and carries the swash plate 13.

The thread guide device, with adjustment, comprises, firstly, the thread-guide member 14, which engages the swash plate 13, is adapted to be displaced on a rockable shaft 15 and also 100 engages a slidably mounted shaft 18 in such a way that it can turn or rock about the shaft but communicates its reciprocating movements thereto. The shaft 18 is journalled in links 19 and 20 which carry the rockable shaft 15. Two torsion 105 springs 21 and 22 bear on the links 19 and 20. They act to keep the thread-guide member 14 down in engagement with the swash plate and prevent play or lost motion. Fixed on the hub 110 of the link 20 outside the casing is an adjusting

arm 24 carrying a set screw 26. A scale 25 (see Fig. 6) is mounted on the casing wall 23, opposite the adjusting arm 24. 16 represents the two longitudinally displaceable thread guides on the 5 end of the shaft 18.

The ratchet mechanism is arranged to actuate a disc 43 designed, for example, as an eccentric and secured on the shaft 44. The eccentric 43 is connected to a wire or steel band 42, which is 10 also led over a disc 41 on the shaft 40. This shaft 40 carries a worm wheel 39 and is pivotally mounted in the casing wall 23 (see Figs. 1, 2, 3 and 4). The shaft 40 (Fig. 5) is displaceably mounted and may be formed, outside the casing, 15 as a handle. The worm wheel 39 meshes with the worm 38 (Figs. 2 and 3) on the shaft 37. On the other end is the worm 36 meshing with the worm wheel 35. The shaft 32 which carries the worm wheel 35, also carries ratchet wheel 34, 20 outside the casing. The wheel 34 coacts with the pawl 33 mounted on the rod 30 pivoted on the shaft 32 (Figs. 3 and 5). This pivoted rod has a slot 31 engaged by a pin 29 on the wheel 27 of the main shaft 10. The pin 29 is adjustable 25 in a diametrical groove 28 of the wheel 27 for varying the effective stroke of the ratchet mechanism. Finally, as can be seen from Figs. 2 and 3, the shaft 40, which is mounted, on the one hand, in the casing, is also mounted in a small 30 gate in the wall of the casing.

The new winding machine operates in the following manner:

The thread-guide member 14 is set, in relation to the swash plate 13, to the desired winding amplitude by means of the adjusting device 24, 35 26, and said amplitude is set on the scale 25 by means of the set screw 26. If a different amplitude is desired, the adjusting arm 24 is shifted, thus correspondingly displacing the guide member 14 in relation to the swashplate 13. By means 40 of this possibility of adjustment, the invention enables a great variety of winding amplitudes to be produced with a uniform amplitude of movement of the thread guide. When this adjustment has been effected the machine can be 45 started.

The motor-driven shaft 1 causes the friction wheel 2 to revolve the friction wheel 3, thus rotating the bobbin and the swashplate shaft 10 by means of known pinion gearing. At the same 50 time, the yarn is wound on to the bobbin 5, the

diameter of which consequently begins to increase, thus tending to speed up the rate at which the thread is wound. In order to maintain said rate within uniform limits as the bobbin diameter increases, the ratchet mechanism actuated from the main shaft 10, comes into operation, in that, at each revolution of the main shaft, the eccentrically mounted ratchet lever 30, with the trailing pawl 33, describes an intermittent motion which can be adjusted to suit the thickness of the yarn and is transmitted to worm gear 35-39, thus gradually coiling the steel band 47 on the disc 41. This rocks the shaft 44 and therefore also the rocking arm 45 mounted thereon. This rocking motion is transmitted through the roller 46 to the friction wheel 2, thus causing it to shift in relation to the friction wheel 3, thereby gradually reducing the speed of the bobbin and thus keeping the rate of winding of the yarn at a uniform level.

When the bobbin has attained the desired diameter, the displaced friction wheel 2 is returned to its original position, for which purpose the worm 39 is brought, by means of the shaft 40, out of engagement with the worm wheel 37 and returned to its original position, for example by means of a manual shaft. On that position being reached the worm 39 is once more brought into gear with the worm wheel 37.

I claim:-

In a yarn winding machine for winding at a uniform rate as the diameter of the bobbin increases, the combination with friction drive gearing including a displaceable member, at least one rotatable bobbin shaft operatively connected 110 with the friction gearing, a reciprocable thread guide, a rotatable swash plate also operatively connected with the friction gearing, and a slidably mounted rod carrying the thread guide, of a member turnably but non-slidably mounted 115 on the rod to engage the swash plate, means whereby the member can be set in different angular positions according to the required amplitude of reciprocation of the thread guide, ratchet mechanism connected with the friction gearing 120 and positively operable simultaneously with the rotation of the bobbin shaft and reciprocation of the thread guide, and means operable by the ratchet mechanism for progressively shifting the displaceable member of the friction gearing. 125 ERNST SCHWEIZER.
